UNITED STATES PATENT OFFICE.

FRANK H. NICHOLSON, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed September 12, 1918. Serial No. 253,747.

To all whom it may concern:

Be it known that I, FRANK H. NICHOLSON, a citizen of the United States, residing at Wilkinsburg, in the county of Allegheny and State of Pennsylvania, have invented certain new and useful Improvements in Railway-Traffic-Controlling Apparatus, of which the following is a specification.

10 My invention relates to railway traffic controlling apparatus, and particularly to apparatus of the type in which an automatic brake application is caused if a car or train exceeds a certain speed limit under 15 certain traffic conditions, or violates other restrictions which may be imposed due to fixed conditions or to traffic conditions in advance of the car or train.

Various schemes have been proposed in 20 the past whereby a train is permitted to pass a caution signal and proceed to the stop signal without an automatic brake application, provided the train is so controlled by its operator that its speed never exceeds a 25 predetermined maximum speed limit, which limit is determined by the automatic device carried by the train or car. The speed limit thus determined by the automatic device on the car or train is made to decrease gradually with the progress of the train through 30 the block, so that the speed limit at any point within the block will be the same as the speed which would result from a brake application of known intensity initiated at 35 the entrance to the block. In other words, the speed limit thus obtained may be represented upon a speed-distance diagram by a curve, which curve may be made to coincide with a braking curve representing the known 40 braking of the given train in the given block.

It is obvious that the braking distance and the braking curve for a given train depend upon the profile and alignment of the track over which the train is running; for example, if the grade is descending, the braking distance will be greater than if the grade is ascending or if the track is level.

In a fixed signal system where the block lengths are determined by the braking curves or the braking distances for a given train at a given speed, and the braking distances vary greatly in length, there will be a large number of different braking curves, and a correspondingly large number of dif-

ferent block lengths. If the block length 55 is equal to the respective braking distance plus a factor of safety, it is obvious that the location of the caution signal fixes the high speed end of the braking curve, and accordingly the operators of trains or cars running 60 through such blocks are instructed and are accustomed to start the braking of the train at the location of the caution signal.

If, to a railroad equipped with fixed signals, as above described, it is proposed to 65 apply an automatic train control system producing speed limit curves coinciding with the braking curves, it is apparent that the automatic device carried by the train must be capable of producing a different speed 70 limit curve for each block length, or at least for each group of nearly equal block lengths, and furthermore, it must be capable of selecting and producing at the entrance of any block, the particular speed limit curve 75 which coincides with the braking curve for the given train in that particular block. These requirements have resulted in certain complications and certain difficulties which it is proposed to avoid by means of 80 the present invention.

Since the block length is equal to the braking distance plus a factor of safety, it is apparent that the speed limit curve determined by the automatic device discussed 85 above is not the braking curve representing the shortest stopping distance with the given train at the maximum speed. The speed limit curve really represents a normal stop of the train, when its speed is reduced, immediately after passing the caution signal, by a brake application of a degree just sufficient (no more or no less) to bring it to rest at the stop signal.

Such accurate handling of the train requires a degree of skill not usually found in train operators, or it requires a form of air brake by which the braking effort can be increased or lessened at will and by the exact degree required to keep the train close 95 to but just below the speed limit curve traced by the automatic device carried by the train or car. The feature in the air brake system by which the braking effort following a brake application is lessened in degree or "graduated off" at will, is known 100 as the "Graduated release" feature, and since this feature is not provided in the air brake

systems of many trains or cars, it is apparent that it is not practicable to control such trains or cars in the manner presupposed in the above discussed automatic control system.

I have found, however, that the required safety and accuracy may be obtained if the operators of such trains or cars control them between the caution signal and stop signal by two full service brake applications, separated by a period in which the brakes are released and the train is allowed to drift. By this method, as soon as the caution signal is passed, the speed of the train is reduced along a braking curve shorter than that which would be traced by the automatic device discussed above, and the speed is thereby quickly brought below a certain intermediate or so-called controlled speed. The brakes may then be released, and the train allowed to drift to a point of second application, which obviously is the point at which a second full service brake application will bring the train to rest at the stop signal. To control a train in this manner the operator will, as the train passes the caution signal, make a full service brake application, and will then place his brake valve handle at the lap position and retain the application until the train speed has been brought to the intermediate or controlled limit. He will then release the brakes and allow the train to drift to the point of second application where a second full service application will be made, which application will be held until the train has been brought to rest, or its speed brought below a predetermined low limit.

In actual practice the block lengths on most railroads do not correspond exactly with maximum braking distance plus the fixed factor of safety. In such cases, the drifting distance between the two brake applications will vary in different blocks, the variation depending upon the extent to which the actual block lengths depart from the lengths determined by braking distance plus factor of safety.

It will be noted that by the use of this two-application stop the speed of the train never exceeds the speed limit curve which would be set by the automatic device discussed above, and if it can be assured that the required or predetermined brake application will be made at the caution signal and at the second application point, and that each application will be held until the predetermined lower speed is reached, it is obvious that automatic means for determining the theoretical speed limit curve is not required, and the complications and difficulties involved in its operation are avoided.

One feature of my invention, then, is the provision of means for preventing an automatic application of the brakes if the opera-

tor controls the train by the "two-application stop" method which I have explained, that is, if he manually effects the braking inherently required to keep the train below the safe speed limit at every point in the block in the rear of a stop signal.

Another feature of my invention is the provision of means whereby the operator of the car or train can suppress or prevent the operation of the automatic device for applying the brakes, by the act of applying the brakes in the usual manner; that is, by causing a brake pipe or equalizing reservoir reduction of a predetermined amount known to be sufficient to bring the train to a stop or to a predetermined lower speed at a point determined by the track or traffic conditions in advance.

Still another feature of my invention is the provision of means for penalizing the operator of the car or train when the operator fails to observe or obey the roadside signal, by causing the car or train to come to a full stop whenever the automatic application of the brakes has occurred.

I will describe one form and arrangement of apparatus embodying my invention, and will then point out the novel features thereof in claims.

In the accompanying drawings, Fig. 1 is a view, partly diagrammatic, showing one form and arrangement of vehicle carried apparatus embodying my invention. Fig. 2 is a diagrammatic view showing one form of trackway apparatus which may be employed in connection with the apparatus shown in Fig. 1.

Similar reference characters refer to similar parts in each of the views.

Referring first to Fig. 1, it is understood that all of the apparatus shown herein, except a contact rail A, is carried by a railway vehicle, such as a car or locomotive, and that such vehicle is provided with a braking system of the usual fluid pressure type. The only part of this braking system which is shown in the drawing, however, is the operating handle of the engineer's brake valve, this part being designated "Brake valve handle." Attached to this handle is a cam 2 which controls a valve 4 in a casing 3, this valve being biased to the closed position by a spring 5. The cam is so designed that valve 4 is open when the valve handle is in "Running," "Release" and "Lap" positions, but closed when the handle is in "Service" or "Emergency" position. When the valve 4 is open, it opens a pipe 6 to atmosphere through a port 7.

The reference character V designates a valve device comprising a body having a large cylinder 8 at one end and a smaller cylinder 9 at the other end. The large cylinder is connected with the equalizing reservoir of the braking system through a pipe 130

12, and the small cylinder 9 is connected with the feed valve of the braking system through a pipe 13. The large cylinder contains a piston 10, and the small cylinder contains two pistons 11 and 15. All three pistons are rigidly connected by a rod 14 so that they move in unison. When the brakes are released, the pressure in the feed valve is, of course, substantially the same as that in the equalizing reservoir, hence at such time the three pistons 10, 15 and 11 are moved to the extreme right owing to the fact that the area of piston 10 is greater than that of piston 11, and because the chamber between pistons 10 and 15 is connected to atmosphere through a port 66. When a service application of the brakes is made, however, the pressure in the equalizing reservoir is reduced while that in the feed valve remains substantially the same as before. The relative areas of the pistons are such that when the pressure in the equalizing reservoir is reduced by an amount corresponding to the required brake application, the actual pressure on pistons 11 and 15 exceeds that on piston 10 so that the pistons then move to the left. When the pistons are at the extreme right, as shown in the drawing, the pipe 6 is opened to cylinder 9 between pistons 11 and 15, but when the pistons move to the left piston 11 covers the port by which pipe 6 enters the valve body and so disconnects this pipe from cylinder 9.

Reference character 16 designates a pipe the upper end of which leads into the upper end of a cylinder 17 which is integral with the casing of the valve device V. The upper end of the cylinder 17 also communicates with cylinder 9 by a port 20 which is so located that it is always between pistons 11 and 15 regardless of the position of these parts. The connection between pipe 16 and port 20 is, however, controlled by a valve 18 in such manner that when this valve is in its uppermost position, as shown in the drawing, it disconnects pipe 16 from port 20, but that when the valve moves downwardly pipe 16 is opened to port 20 and so to cylinder 9. The lower end of the cylinder 17 is connected with a pipe 21, which is normally closed but which may at times be opened to atmosphere by means hereinafter explained. The valve 18 is provided with a port 18^a of small area, so that normally the same pressure exists on both the upper and the lower sides of this valve. At such times the valve occupies its uppermost position owing to the action of a spring 19. If, however, pipe 21 is opened to atmosphere, the pressure on the upper surface of the valve overbalances the pressure exerted by the spring 19 so that the valve moves downwardly and connects pipe 16 with port 20.

The lower end of pipe 16 is connected with a brake application valve device F which I

will now describe. This valve device comprises a body 77 in which is a slide valve 78. The slide valve is controlled by a piston 79 which is rigidly connected with the valve and which operates in a cylinder 77^a integral with the body of the valve. The valve body 77 is constantly connected with the main reservoir of the braking system through a pipe 81. When the slide valve occupies its extreme right-hand position, as shown in the drawing, the main reservoir is connected with the feed valve of the braking system through a pipe 82, so that the brakes are then under the control of the operator of the vehicle; but when the slide valve is shifted to the left it covers the port leading to pipe 82 and so disconnects the feed valve from the main reservoir, whereby the operator cannot then release the brakes by manipulation of his brake valve handle. B. P. represents a pipe opening into the seat on which the slide valve operates, and which pipe leads to the brake pipe of the braking system. When the slide valve is in the position shown, it covers the pipe B. P. so that no automatic application of the brakes can occur. When the slide valve moves to the left, however, a cavity 86 in the slide valve connects the pipe B. P. with an exhaust port 83 so that the pressure in the brake pipe is reduced and an automatic application of the brakes occurs.

The slide valve 78 and piston 79 are biased to the right by a spring 80, so that when the fluid pressures on the two sides of the piston are equal the slide valve occupies its right-hand position as shown. The pressures on the two sides of the piston are equal when the upper end of pipe 16 is closed for the following reason: Main reservoir pressure is constantly exerted on the right-hand side of the piston, and the piston is provided with a small port 79^a through which the main reservoir pressure may flow to the left-hand side of the piston. The left-hand end of cylinder 77^a is normally connected with pipe 16 through a pipe 90 and a cavity 85 in the slide valve. When, therefore, the upper end of pipe 16 is closed, the fluid pressures on the two sides of the piston are equal so that the slide valve occupies its right-hand position owing to the influence of spring 80.

I will now assume that the upper end of pipe 16 is opened to atmosphere through pipe 6 and valve 4, as hereinbefore explained. This causes a reduction in pressure on the left-hand side of piston 79, so that the pressure on the right-hand side of this piston is then sufficient to move the piston and the slide valve 78 to the left. This movement of the slide valve opens pipe B. P. to atmosphere through the exhaust port 83 and so cause an automatic application of the brakes. This movement of the slide valve also dis-

- connects the feed valve pipe 82 from the main reservoir and so removes the control of the brakes from the operator of the car or train. This movement of the slide valve, 5 furthermore, disconnects pipe 16 from pipe 90 and connects the latter pipe with a pipe 87, which is normally opened to atmosphere through an exhaust port 88. The left-hand end of cylinder 77^a is then connected with 10 atmosphere through this exhaust port, so that the slide valve remains in its left-hand position until the exhaust of air from pipe 87 is discontinued. This exhaust may be discontinued by means of 15 a push button valve, 89, which is located at such position on the vehicle as to require that the operator shall leave his cab and descend to the ground in order to operate the valve. It follows, therefore, that 20 once an automatic application of the brakes has occurred, the vehicle must come to a full stop before the brakes can be released. That is, the construction of this valve device "F" is such that after it has been moved to brake 25 applying position, the upper end of pipe 16 may be disconnected from atmosphere without affecting the position of the valve device, and the valve device can only be returned to its initial position by the operation of the 30 push button 89.
- The operation of the apparatus thus far described is as follows:
- As long as pipe 21 is closed, plunger 18 35 remains in uppermost position, so that pipe 16 is closed and no automatic application of the brakes occurs. When, however, pipe 21 is opened to atmosphere, valve 18 moves downwardly so that pipe 16 is connected with cylinder 9 of valve device V. If the pistons 10, 15 and 11 of this valve device are in the positions shown, fluid pressure can flow 40 from pipe 16 into pipe 6, and if valve 4 is opened, the fluid can pass through this valve and out to atmosphere through port 7. Under 45 such conditions, therefore, the pressure in pipe 16 is reduced so that an automatic application of the brakes is effected by valve device F. If, however, the brake valve handle is at such time in the service or emergency 50 position, valve 4 is closed so that the exhaust of air from pipe 16 is prevented at this point. Furthermore, if the equalizing reservoir pressure has already been reduced by such an amount as to cause the predetermined 55 service application of the brakes, pistons 10, 15 and 11 will have been moved to the extreme left, thereby disconnecting pipe 6 from pipe 16. In this event the reduction of pressure in pipe 16 will be prevented by 60 piston 11, so that an automatic application of the brakes does not occur. It will be seen, therefore, that the automatic application is prevented if the brake valve handle is in service or emergency position, or if an application of the brakes is already in effect; 65

and it will furthermore be seen that if the predetermined service application is already in effect, the brake valve handle may be returned to the lap position and an automatic application will still be prevented.

The lower end of pipe 21 terminates in a valve body D, and this body is provided with a port 24 which is opened and closed by a slide valve 23. When the port 24 is covered by the slide valve, pipe 21 is closed so that 70 valve 18 is in its uppermost position. That is, the air pressures on the two sides of this valve are equal and the valve is pushed upwardly by spring 19. When, however, the slide valve 23 is moved upwardly, port 24 75 is uncovered, so that pipe 21 is opened to atmosphere, whereupon valve 18 moves downwardly owing to the reduction in the air pressure on its under side.

It will, of course, be observed that when 80 port 24 is opened by slide valve 23, pipe 16 is connected with atmosphere through the port 18^a and pipe 21 even though piston 11 covers pipe 6 or valve 4 is closed. The area of port 18^a is so small, however, that the rate 85 of exhaust through this port is not sufficient to cause an automatic application of the brakes.

Slide valve 23 is controlled by a speed responsive device, which, as here shown, is 90 in the form of a centrifuge C. This centrifuge comprises a hollow shaft 25 journaled in a bearing 26 and provided with 95 diametrically disposed arms 25^a, in which are pivotally mounted the bell cranks 27 of the 100 centrifuge. Attached to the hollow shaft 25 is a spur gear 22 which is connected through suitable gearing (not shown) with a wheel or axle of the vehicle, so that while 105 the vehicle is in motion the shaft 25 is constantly rotated at a speed proportional to the speed of the vehicle. The inner arms of bell cranks 27 are provided with slots which 110 coact with a pin 35 attached to a rod 28, which rod passes through the hollow shaft 115 25 and is free to move longitudinally therein. The lower end of the rod 28 is connected with slide valve 23, so that longitudinal movement of the rod 28 causes a corresponding movement of the slide valve on 120 its seat. The parts are so arranged and proportioned that when the bell cranks 27 of the centrifuge are in the closed position, the slide valve 23 covers the port 24, but that when these levers fly outwardly, due to centrifugal action, the rod 28 is moved upwardly, so that the slide valve 23 uncovers the port 24 and thus opens pipe 21 to atmosphere.

Suitable means are provided for biasing 125 the rod 28 downwardly, thus opposing the natural tendency of the centrifuge to open while the vehicle is in motion. As here shown, this biasing means is arranged to exert three different pressures on the rod, 130

thus imposing three different speed limits on the vehicle. This biasing means comprises a cylinder 29 in which is a piston 30 attached to the upper end of the rod 28. 5 Also located in the cylinder 29 is a spring 32 one end of which abuts against the piston 30 and the other end against a plunger 31 also movable within the cylinder. The spring 32 is so adjusted that when the plunger 31 is in its uppermost position, as shown in the drawing, the pressure exerted on the rod 28 through the piston 30 is of such value, that as long as the vehicle does not exceed a predetermined low speed, such as 15 miles 10 per hour, the centrifuge will not open, but that if the vehicle exceeds this speed the centrifuge will overcome the action of the spring and so will move the slide valve 23 to uncover port 24. This spring then, when 15 expanded as shown, imposes on the vehicle what may be termed a "low speed limit."

Entering the cylinder 29 at the upper end is a pipe 34 which at times admits fluid pressure to the upper surface of plunger 31. 25 When this occurs, plunger 31 is driven downwardly until it engages with a fixed stop 38, thus compressing the spring 32 and so increasing the pressure exerted by this spring against the head 30. The pressure 30 opposing the action of the centrifuge is then such as to permit the vehicle to travel at a speed not to exceed a predetermined intermediate value, such as 35 miles per hour, without opening the centrifuge. The speed 35 limit thus imposed may be termed the "Intermediate speed limit."

In order to permit the vehicle to travel at high speed, such as 65 miles per hour, without opening the centrifuge, I provide 40 a pipe 33 which enters the cylinder 29 directly above the piston 30. When fluid pressure is supplied to this pipe 33, it causes a high pressure to be exerted directly on the piston 30, which pressure added to that of 45 spring 32 permits the vehicle to travel at high speed (herein assumed to be 65 miles per hour) without causing the centrifuge to open. This pressure, then, imposes what may be termed the "High speed limit."

50 Fluid pressure, usually air, is at times supplied to the pipe 34 from a reservoir or other suitable source, this supply being controlled by a valve 36 which in turn is controlled by an intermediate speed magnet 55 M^I . This magnet and valve are so arranged that when the magnet is de-energized the valve disconnects the pipe 34 from the source of pressure and connects this pipe with atmosphere through an exhaust port 37; but 60 that when the magnet is energized the valve connects the pipe 34 with the source of fluid pressure and closes the exhaust port.

The supply of fluid pressure to the pipe 33 is controlled in a similar manner by a 65 valve 36^a and a high speed magnet M^H .

The intermediate speed magnet M^I is controlled by an intermediate speed relay R^I , the circuit being from one terminal B of a source of current, through contact 41^a of relay R^I , wire 39, magnet M^I , and wire 40 70 to the other terminal O of the source of current. The source of current itself and the parts of the circuit which do not pass in the parts of the apparatus shown in the drawing are omitted for the sake of simplicity. It 75 will be seen that magnet M^I is energized or de-energized according as relay R^I is energized or not. The high speed magnet M^H is similarly controlled by a contact 41 of a high speed relay R^H , the circuit for this 80 magnet being obvious from the drawing. The relays R^H and R^I are controlled by a polarized relay P in such manner that one relay or the other is energized according as armature contact 42 of the polarized relay 85 P is swung in one direction or the other. The circuit for relay R^H is from one terminal B of a source of current through contact 42-49 of relay P, wires 43 and 44, relay R^H and wire 45 to the other terminal O 90 of the source of current. The corresponding circuit for relay R^I is controlled by contact 42-50 of polarized relay P and will be obvious from the drawing.

The circuits which have just been traced 95 for relays R^H and R^I are in the nature of pick-up circuits, and are merely for the purposes of preliminary energization of these relays. Each relay is further provided with a holding circuit including a contact controlled by a shoe 51 which is arranged to coact with ramp rails A located in the trackway. This shoe 51 controls two contacts 46 and 52 which contacts are normally closed but are opened each time that shoe 51 is raised by a ramp rail A. The holding circuit for relay R^H is from one terminal B of a source of current, through contact 46, wire 47, contact 48 of relay R^H , wire 44, winding 100 of relay R^H , and wire 45 to the other terminal O of the same source of current. The circuit for relay R^I is controlled by contact 52 and by a contact 48^a of the relay itself, and will be obvious from the drawing without further explanation. 110

One terminal of the polarized relay P is connected with a wheel or axle of the vehicle at the point indicated by the reference character G, while the other terminal of this relay is connected with the shoe 51 by means of a wire 53. Means are provided in the trackway, as hereinafter explained, for at times connecting a suitable source of current with ramp rail A and a track rail of the railway. It follows that when the shoe 115 51 engages with ramp rail A, relay P will be energized in one direction or the other according as the positive terminal of the last-mentioned source of current is connected with ramp rail A or with the track rail; ob- 120 125 130

viously, if this source of current is not connected with both the ramp rail and the track rail, relay P will remain deenergized. I will assume for purposes of discussion that 5 when the positive terminal of the trackway source is connected with the ramp rail A, relay P is energized in such direction as to close contact 42-49 and so to energize the high speed relay R^H. This energization I 10 will term "the positive energization of relay P."

Referring now to Fig. 2, the reference characters T and T^a designate the track rails of a railway along which traffic normally 15 moves in the direction indicated by the arrow. These rails are divided by suitable means, such as by insulated joints 65, into a plurality of successive block sections J-K, K-L, etc. Located adjacent the entrance 20 of each block is a signal which is designated by the reference character S with an exponent corresponding to the location of the signal. The controlling means for these signals forms no part of my invention, and 25 hence is omitted from the drawing for the sake of simplification. Each signal is adapted to indicate "Stop" when the corresponding block is occupied, "Caution" when the corresponding block is unoccupied 30 and the block next in advance is occupied, and "Proceed" when the corresponding block and the block next in advance are both unoccupied; for example, as shown in Fig. 2, the block immediately in advance of 35 location L is occupied by a vehicle W, so that signal S^L indicates "Stop," signal S^K indicates "Caution," and signal S^J indicates "Proceed."

Located at or near the entrance end of 40 each block is a ramp rail A, and located at a suitable distance in the rear of each ramp rail A is a second ramp rail A'. Each of these ramp rails is arranged to coact with the vehicle-carried shoe 51, shown in Fig. 1, 45 in such manner that the shoe is elevated to open contacts 46 and 52 each time that the shoe passes over one of these rails. Current is at times supplied to each ramp rail A by an adjacent source of current E, and, similarly, current is at times supplied to each 50 ramp rail A' by an adjacent source E'. Considering first ramp A, the supply of current therefor is controlled by contacts 54 and 55 operated by the adjacent signal 55 S, the control being such that when the signal indicates proceed, the positive terminal of the source E is connected with the ramp rail A and the negative terminal with the lower track rail T; but that when the signal 60 indicates caution, the polarity is reversed, so that the negative terminal of the source E is connected with ramp rail A and the positive terminal with the track rail T. When the signal indicates stop, the source E 65 is disconnected from ramp rail A so that this

rail is then dead. When the signal is in the proceed position (see signal S^J) the positive terminal of battery E is connected with ramp rail A through contact 55 and wire 57, and the negative terminal is connected 70 with the track rail T through contact 54 and wires 59 and 58. When, however, the signal indicates caution (see signal S^K), the positive terminal of battery E is connected with rail T, through wire 61, contact 54 and 75 wires 59 and 58; whereas the negative terminal is connected with ramp rail A, through wire 60, contact 55 and wire 57.

The connection between each battery E' and the corresponding ramp rail A' is controlled 80 by a contact 56 operated by the adjacent signal, the control being such that the positive terminal of the battery is connected with the ramp A' when the adjacent signal indicates proceed or caution, but that the connection is broken when the signal indicates stop.

The operation of the entire apparatus is as follows:

Referring first to Fig. 2, I will assume 90 that while the vehicle W is in the position shown on the drawing, a second vehicle equipped with the apparatus shown in Fig. 1, approaches block J-K. As this second vehicle passes over ramp rail A' in the rear 95 of location J, the shoe 51 will be elevated to open the holding circuit of whichever relay R^H or R^I was previously energized, but at the same time polarized relay P will be energized in such direction as to close 100 the pick-up circuit for the high speed relay R^H, because the positive terminal of the adjacent source E is connected with this ramp rail. Then as the shoe 51 passes off of rail A', the holding circuit for this relay R^H will 105 be closed at contact 46. High speed magnet M^H is then energized so that the vehicle can proceed at 65 miles per hour or less. Ramp rail A at location J is connected with the positive terminal of its battery E, so that the 110 same operation takes place as the vehicle passes over this ramp rail. The vehicle may then proceed into block J-K at full speed. Rail A' immediately in the rear of location K is connected with the positive terminal of 115 its battery E', so that the same operation again takes place as the vehicle passes over this ramp rail. Ramp rail A at location K is, however, connected with the negative terminal of its battery E, so that as the vehicle 120 passes over this ramp rail polarized relay P will be energized in such direction as to close the pick-up circuit for the intermediate speed relay R^I. The high speed relay R^H, of course, becomes de-energized, because 125 its holding circuit is opened at contact 46. The opening of relay R^H causes the high speed magnet M^H to become de-energized, so that the supply of fluid pressure to pipe 33 is discontinued and this pipe is opened 130

to atmosphere. The intermediate speed magnet M^1 becomes energized, however, so that fluid pressure is supplied to the cylinder 29 above the plunger 31. Assuming that

5 the vehicle is traveling at the high speed limit, that is, 65 miles per hour at this point, it, of course, follows that centrifuge C will open, so that slide valve 23 will be elevated to uncover port 24. If the engineer or

10 operator of the vehicle recognizes the indication given by signal S^k and moves his brake valve handle to service position just before this ramp rail A is reached, the pipe 6 will not be connected to atmosphere and so an

15 automatic application of the brakes will be prevented. Likewise after the service application of the brakes has been effected the pistons 10, 15 and 11 of the valve device V will move to the left, so that the operator

20 may return his brake valve handle to the lap position and the automatic brake application will still be prevented. The speed of the vehicle will then be gradually reduced, as indicated by the curve 74. When

25 the speed is reduced to slightly under 35 miles per hour the centrifuge will close, so that the operator may release the brakes by the proper manipulation of his brake valve handle and then proceed at a constant speed,

30 as indicated by line 75, until ramp rail A' is reached. That is, the operator may release the brakes at the point 71 in Fig. 2 or shortly thereafter. Ramp rail A' in the rear of location L is disconnected from its source

35 of current, so that as the shoe 51 passes over this ramp rail the intermediate speed relay R^1 will become de-energized. This causes de-energization of the intermediate speed magnet M^1 , so that the supply of air to the

40 upper end of cylinder 29 is discontinued. If the vehicle is still traveling at 35 miles per hour or slightly less, the centrifuge C will again open, whereupon port 24 will again become opened and valve 18 will move downwardly to connect pipe 16 with the interior of valve device V. If, just prior to reaching this ramp rail A', the operator again moves his brake valve handle to the service position, an automatic application of the

45 brakes will again be prevented and the brake valve handle can be returned to the lap position after the service application has become effective. The brakes now being applied, the speed of the vehicle will be

50 reduced, as indicated by the curve 76 in Fig.

2. When the point 73 is reached, that is, when the speed of the vehicle is reduced to 15 miles per hour, centrifuge C will close so that the brakes may then be released and

55 the vehicle may then proceed at this low speed limit into the block occupied by the vehicle W.

In the foregoing description of the operation of the apparatus I have assumed that

60 the operator of the vehicle controls the vehicle manually in accordance with the indications given by the signals S^k and S^l . I will now assume that the vehicle approaches signal S^k at 65 miles per hour, but that the operator does not observe the indication

70 given by this signal, that is, that he does not move his brake valve handle to cause an application of the brakes. Then as the vehicle passes over the ramp rail A adjacent this signal, the valve 18 will move downwardly

75 so that pipe 16 will be connected with atmosphere through pipe 6 and valve 4. This will cause operation of valve device F to effect an automatic application of the brakes. When the speed has been reduced to a little

80 less than 35 miles per hour, the centrifuge will close so that valve 18 will return to its initial position, but this does not affect valve device F. The brake application will continue, therefore, until the vehicle is

85 brought to a full stop, a considerable distance in the rear of signal S^l . Again, let it be assumed that the operator applies the brakes at the point 70 by the proper manipulation

90 of the brake valve handle and again releases the brakes at point 71, so that the vehicle proceeds at 35 miles per hour or less, as indicated by the line 75. Then let it be assumed that at ramp rail A', that is at point 72, the operator fails to acknowledge the stop indication of signal S^k by a further manipulation

95 of the brake valve handle. Valve 18 will again move downwardly, so that pipe 16 will then be opened to atmosphere through pipe 6 and valve 4, thus causing an automatic application of the brakes which will bring the vehicle to a stop in the rear of signal S^l .

100 It will be noted that in the event that an automatic application occurs, the brakes cannot be released until the vehicle is brought to a full stop, because the release button 89 can be reached only from the ground. This full stop serves as a penalty to the operator for non-observance of the signal indications.

105 Although I have herein shown and described only one form of apparatus embodying my invention, it is understood that various changes and modifications may be made therein within the scope of the appended claims without departing from the spirit and scope of my invention.

110 Having thus described my invention, what I claim is:

1. In combination, a railway vehicle provided with a braking system, automatic apparatus for causing an automatic application of the brakes when said vehicle exceeds certain prescribed limit speeds during its progress along the track, and means for preventing operation of said automatic apparatus said means being effective only when the brakes have been applied manually by the operator of the vehicle.

115 2. In combination, a railway vehicle pro-

120

125

130

vided with a braking system, automatic apparatus for causing an automatic application of the brakes when said vehicle exceeds certain prescribed limit speeds during its progress along the track, governing means under the control of the operator for governing the speed of the vehicle, and means dependent upon the operation of said governing means to a degree sufficient to cause retardation of the vehicle for preventing operation of said automatic apparatus.

3. In combination, a railway vehicle provided with a braking system including a manually operable control device for causing a brake application, automatic apparatus for causing automatic application of the brakes when said vehicle exceeds certain prescribed limit speeds during its progress along the track, and means responsive only to an actual application of the brakes by operation of said control device for preventing operation of said automatic apparatus.

4. In combination, a railway vehicle provided with a braking system including a manually operable control device for causing a brake application, automatic apparatus for causing automatic application of the brakes when said vehicle exceeds certain prescribed limit speeds during its progress along the track, and means dependent upon a brake application of predetermined value by the action of said manually operable control device for preventing operation of said automatic apparatus.

5. In combination, a railway vehicle provided with a braking system including an equalizing reservoir and a feed valve pipe, automatic apparatus for causing a brake application in the event of one ratio of pressures existing in said equalizing reservoir and feed valve pipe when the vehicle exceeds certain prescribed limit speeds during its progress along the track, and means dependent upon a different ratio of pressures in said equalizing reservoir and said feed valve pipe for preventing operation of said automatic apparatus.

6. In combination, a railway vehicle provided with a braking system, automatic apparatus for causing an automatic application of the brakes when said vehicle exceeds certain prescribed limit speeds during its progress along the track, and manually operable means for preventing such automatic application provided the brakes have been applied by the operator of the vehicle, said manually operable means being ineffective to release the brakes after they have been applied by said automatic apparatus.

7. In combination, a railway vehicle provided with a braking system, automatic apparatus for causing an automatic application of the brakes upon a prescribed change in traffic conditions if the speed of the vehicle

exceeds a prescribed value, and manually operable means for preventing such automatic application of the brakes, said means being effective only when the brakes have been applied manually by the operator of the vehicle.

8. In combination, a railway vehicle provided with a braking system including a manually operable brake control device, automatic means for causing an application of the brakes, and means for preventing operation of said automatic means which said brake control device is in brake-applying position and for continuing to prevent operation of said automatic means after said device is subsequently restored away from brake-applying position if and while a brake application of predetermined value is in effect due to operation of said device.

9. In combination, a railway vehicle provided with a braking system, automatic means for causing application of the brakes, and means dependent upon a brake application of at least a predetermined value for preventing operation of said automatic means.

10. In combination, a railway vehicle provided with a braking system including a manually operable device for causing application of the brakes, automatic apparatus for also causing application of the brakes under certain traffic conditions, and means for preventing operation of said automatic apparatus while said device is in position to initiate a brake application and also after said device has been restored away from initiating position if and while a brake application of at least predetermined value is in effect due to said device having been in initiating position.

11. In combination, a railway vehicle provided with a braking system, a centrifugal device on the vehicle, means for opposing the opening of said centrifugal device by a variable force whereby if the actual speed of the vehicle at any instant exceeds the permissive speed corresponding to the force then opposing the centrifugal device the said device will open, automatic means controlled by said centrifugal device for causing a brake application when said device opens, and means for preventing operation of said automatic means if the brakes have been applied by the operator of the vehicle.

12. In combination, a railway vehicle provided with a braking system, means on the vehicle for establishing several permissive speeds, speed responsive means on the vehicle, automatic apparatus controlled jointly by said two means for causing an application of the brakes if the actual speed exceeds the permissive speed at any given instant, and means for preventing operation of said automatic apparatus, said means be-

ing effective only when the brakes have been applied by the operator of the vehicle to cause retardation of the vehicle.

13. Railway traffic controlling apparatus comprising a plurality of block sections, a ramp rail A for each section located adjacent the entrance end of the section, a second ramp rail A' for each section located in the rear of the entrance end of the section; means for each rail A for energizing the rail with current of positive polarity when the corresponding section and the section next in advance are unoccupied, for energizing the rail with current of negative polarity when the corresponding section is unoccupied and the section next in advance is occupied, and for deenergizing the rail when the corresponding section is occupied; means for each rail A' for energizing the rail with current of positive polarity when the corresponding section is unoccupied and for de-energizing the rail when the corresponding section is occupied; automatic apparatus on a vehicle controlled by said ramp rails for causing an automatic brake application if the vehicle exceeds a predetermined high speed limit after passing a positively energized rail, if the vehicle exceeds a predetermined intermediate speed limit after passing a negatively energized rail, and if the vehicle exceeds a predetermined low speed limit after passing a de-energized rail; and means acting to prevent operation of said automatic apparatus if the operator of the vehicle applies the brakes manually when passing a negatively energized rail and a de-energized rail.
14. Railway traffic controlling apparatus comprising a plurality of block sections, a ramp rail A for each section located adjacent the entrance end of the section, a second ramp rail A' for each section located in the rear of the entrance end of the section; means for each rail A for energizing the rail with current of positive polarity when the corresponding section and the section next in advance are unoccupied, for energizing the rail with current of negative polarity when the corresponding section is unoccupied and the section next in advance is occupied, and for de-energizing the rail when the corresponding section is occupied; means for each rail A' for energizing the rail with current of positive polarity when the corresponding section is unoccupied and for de-energizing the rail when the corresponding section is occupied; automatic apparatus on a vehicle controlled by said ramp rails for causing an automatic brake application if the vehicle exceeds a predetermined intermediate speed limit after passing a negatively energized rail, if the vehicle exceeds a predetermined low speed limit after passing a de-energized rail, and for permitting movement of the vehicle at high speed without causing an automatic brake application after passing a positively energized rail; and means acting to prevent operation of said automatic apparatus if the operator of the vehicle applies the brakes manually when passing a negatively energized rail and a de-energized rail.
15. Railway traffic controlling apparatus comprising a plurality of block sections, a vehicle; apparatus on the vehicle adapted when in one condition to cause an automatic application of the brakes if the speed exceeds a predetermined intermediate value, and when in another condition to cause an automatic application of the brakes if the speeds exceeds a predetermined lower value; means located adjacent the entrance end of each section for placing said apparatus in the first-mentioned condition when the section next in advance is occupied, means located in the rear of the entrance end of each section for placing said apparatus in the second mentioned condition when such section is occupied, and means on the vehicle acting to prevent operation of said apparatus if the brakes are applied through the usual manually operable means.
16. Railway traffic controlling apparatus comprising a plurality of block sections, a vehicle; apparatus on the vehicle adapted when in one condition to cause an automatic application of the brakes if the speed exceeds a predetermined intermediate value, and when in another condition to cause an automatic application of the brakes if the speed exceeds a predetermined lower value; means for placing said apparatus in the first-mentioned condition when the vehicle enters the section in the rear of an occupied section, means for placing said apparatus in the second mentioned condition when the vehicle reaches a point at a predetermined distance in the rear of an occupied section, and means on the vehicle acting to prevent operation of said apparatus if the brakes are applied through the usual manually operable means.
17. In combination, a railway vehicle provided with a braking system, apparatus for causing an automatic application of the brakes and for preventing release of the brakes after such application has occurred until the vehicle has been brought to a full stop, and means acting when the brakes have been applied manually by the operator of the vehicle for preventing action of said apparatus.
18. In combination, a railway vehicle provided with a braking system, a valve device for causing an automatic application of the brakes and arranged to remain in brake applying position after once being placed there until the vehicle has been brought to a full stop, apparatus for placing said valve device in brake-applying position when the vehicle exceeds certain prescribed limit speeds

during its progress along the track, and means acting when the brakes have been applied manually by the operator of the vehicle for preventing actuation of said valve 5 device to brake applying position.

19. In combination, a railway vehicle provided with a braking system including a manually operable brake valve, automatic means for stopping the vehicle if certain prescribed limit speeds are exceeded by said vehicle in its progress along the track, and means controlled by said manually operable valve and effective only if the valve is held in brake applying position long enough to 15 actually apply the brakes, for preventing said action of said automatic means.

20. In combination, a railway vehicle provided with a braking system including a manually operable device for causing a 20 brake application, automatic apparatus for also causing an application of the brakes, and means dependent upon the operation of said manually operable device for a period of time sufficient to cause retardation of the 25 vehicle for preventing operation of said automatic apparatus.

21. In combination, a railway vehicle provided with a braking system, automatic apparatus for causing a brake application, and 30 means dependent upon the manual application of the brakes to a sufficient degree to cause retardation of the vehicle for preventing operation of said automatic apparatus.

22. In combination, a railway vehicle provided with a braking system including a 35 manually operable device for causing a brake application, automatic apparatus for also causing an application of the brakes, and means dependent upon a brake application of predetermined value by the action of said manually operable device for preventing 40 operation of said automatic apparatus.

23. In combination, a railway vehicle provided with a braking system including a 45 manually operable device for causing a brake application, automatic apparatus for also causing an application of the brakes, and means effective only when the brakes are actually applied through the medium of said 50 manually operable device for preventing operation of said automatic apparatus.

24. Railway traffic controlling apparatus comprising means on a train controlled from the trackway for imposing a continuously 55 effective speed limit under one given condition of traffic in advance of the train, means for automatically applying the brakes of the train if such speed limit is exceeded,

and apparatus under the control of the engineer effective if operated previous to the 60 initiation of such automatic brake application to prevent an automatic application when such speed limit is exceeded.

25. Railway traffic controlling apparatus comprising apparatus on a train controlled 65 from the trackway for automatically applying the brakes if the train exceeds certain continuously effective fixed speed limits determined by traffic conditions in advance, and manually operable means effective to 70 prevent such automatic brake application but ineffective to release the brakes after they have been applied by said automatic apparatus.

26. The method of controlling railway 75 traffic which consists in establishing a continuously effective speed limit on a train determined by traffic conditions in advance of the train, applying the brakes automatically if the established speed limit is exceeded at 80 any moment, and preventing such automatic application if the engineer takes suitable action prior to exceeding the established speed limit.

27. The method of controlling railway 85 traffic which consists in establishing a continuously effective speed limit on a train determined by traffic conditions in advance of the train, applying the brakes automatically if the established speed limit is exceeded at 90 any moment, and preventing such automatic application if the engineer applies the brakes manually prior to exceeding the established speed limit and keeps them applied as long as the speed limit is exceeded. 95

28. In combination, a railway vehicle provided with a braking system, automatic apparatus on the vehicle for causing an automatic application of the brakes, and means for preventing operation of said apparatus if and only if the brakes are actually applied by a manual act on the part of the driver of the vehicle. 100

29. In combination, a railway vehicle, automatic apparatus thereon for causing retardation of the vehicle, and means for preventing operation of said apparatus if and only if the driver performs an act which will actually retard the vehicle. 105

In testimony whereof I affix my signature in presence of two witnesses. 110
